UNITED STATES PATENT OFFICE

OTIS H. HULLINGS, OF ALEXANDRIA, VIRGINIA

LAUNDRY MACHINE

Application filed March 14, 1928. Serial No. 261,468.

This invention appertains to improvements in methods and means for carrying out laundry operations generally, and more particularly the operations of large capacity public service laundries.

An object of the invention is to provide for a method and means which will expedite and otherwise facilitate such operations by permitting of the effective and efficient washing, rinsing, extracting and drying of a comparatively large number of individual bundles or groups of articles to be laundered in one substantially continuous cycle of operation, wherein the actual handling of the articles is avoided throughout a given particular operation, and the usual counting and sorting of the individual washed and dried articles is avoided, thus reducing to a minimum the number of persons usually required for an average laundry operation, and thereby effecting an appreciable saving in the otherwise excessive overhead expenses employed in large capacity public service laundries.

Another object of the invention is to provide the method and means as aforesaid, wherein a comparatively large number of individual bundles or groups of articles to be laundered may be washed and rinsed, either in mixed bulk or in their originally grouped state, in one continuous cycle of operation.

A further object of the invention is to provide a means for the reception of an individual group of articles to be laundered,

in which the several articles of the group will be placed from the original package, received from a householder or other customer, and in which the articles will be retained throughout a complete washing, rinsing, extracting and drying operation as aforesaid, and from which, in the case of so-called dry or damp washes, the articles

will be removed and repackaged for delivery back to the householder or other customer.

A still further object of the invention is to provide a number of the means or devices hereinbefore characterized, and which are of a construction and arrangement, whereby

after having been loaded or filled, each with

one of a corresponding number of individual groups of articles to be laundered, they may be readily and easily nested in a number of equally divided and separated groups; then transported in their entirety to a washing apparatus or machine, and afterwards transferred to and nested in the same grouped arrangement within the movable or rotating element of the apparatus or machine; then,

upon the completion of the washing and rinsing operation of the contents thereof, removed and renested in their equally grouped formation, and transported to the water extracting apparatus or machine, and after-

wards transferred to and nested by individual groups into the latter; then, upon the completion of the water extracting operation, removed from the extracting apparatus or machine and transported in their equally

grouped formation to a drying apparatus or tumbler into the movable or rotating element of which they will be subsequently nested in obtaining in known methods and means now employed in large capacity public service laundries.

Another object of the invention is to provide the method and means as aforesaid, wherein a comparatively large number of individual bundles or groups of articles to be laundered may be washed and rinsed, either in mixed bulk or in their originally grouped state, in one continuous cycle of operation.

A further object of the invention is to provide a means for the reception of an individual group of articles to be laundered,

in which the several articles of the group will be placed from the original package, received from a householder or other customer, and in which the articles will be retained throughout a complete washing, rinsing, extracting and drying operation as aforesaid, and from which, in the case of so-called dry or damp washes, the articles

will be removed and repackaged for delivery back to the householder or other customer.

Another object of the invention is to provide a number of the means or devices hereinbefore characterized, and which are of a construction and arrangement, whereby

after having been loaded or filled, each with

one of a corresponding number of individual groups of articles to be laundered, they may be readily and easily nested in a number of equally divided and separated groups; then transported in their entirety to a washing apparatus or machine, and afterwards transferred to and nested in the same grouped arrangement within the movable or rotating element of the apparatus or machine; then,

upon the completion of the washing and rinsing operation of the contents thereof, removed and renested in their equally grouped formation, and transported to the water extracting apparatus or machine, and after-

vide a slightly modified form of rotor for known makes or types of centrifugal moisture or water extracting apparatus or machines, which will readily adapt the same for the desired nesting therein of a number of the individual wash containing means or devices aforesaid.

A still further object of the invention is to provide for a means or device of the character as hereinbefore set forth, and one in the form of a reticulated or open mesh container for an individual wash, and which, when employed in a rotating cylinder or drum of either a washing apparatus or a drying machine or tumbler, in accordance with the various objects and purposes of the invention, gives ready access to its contents of the washing or rinsing solutions or waters, on the one hand, or the drying air currents, on the other hand, and, at the same time acts to subject its contents to a tumbling movement over the several side walls forming a part of the same, in its first instance of use, and to loosen up and slightly separate the several articles of which its contents may be constituted, in its second instance of use, whereby the articles will be thoroughly cleansed, rinsed and dried.

A further object of the invention is to provide that, in carrying out the hereinbefore described continuous washing, rinsing, extracting and drying of a predetermined number of groups of articles or fabrics in each cycle of operation of the several apparatuses or machines employed for the purpose, additional groups of articles or fabrics will be successively placed within the washing apparatus or machine immediately upon the removal therefrom of the previously washed and rinsed groups of articles or fabrics and the transportation of the same to the other of the several apparatuses or machines in the stated sequence of their operation, so that at no time will any one or more of the latter be idle from the start of an initial cycle of operation to the completion of the laundering of a particular or given number of groups of articles or fabrics to be laundered, or until a predetermined or given time period has elapsed, whereby an appreciable saving in time and labor is effected, not only in a single cycle of operation, but throughout each daily run or operation of the apparatuses or machines.

Another object of the invention is to eliminate, in carrying out the aforesaid continuous washing and rinsing operation, the settling of soil laden froth of the used washing solution or suds on the groups of previously washed articles, such as would occur in the old method of operation of washing machines wherein the used solution or suds is discharged from the latter prior to admitting fresh rinsing water thereto, which elimination is accomplished in a manner that the

used solution or suds is gradually forced out of the machine and from the washed articles by admitting rinsing water to the machine immediately following a washing operation, thus leaving the articles in a semi-rinsed and much cleaner condition than would otherwise be the case and ready for a succeeding rinsing operation upon the complete evacuation of the used washing solution or suds from the machine.

With the foregoing and other equally important objects and advantages in view, the invention resides, in part, in the certain new and useful combinations, constructions and arrangements of parts, and in the method aforesaid, as will be hereinafter more fully described, set forth in the appended claims, and illustrated in the accompanying drawings, in which:

Figure 1 is a vertical longitudinal section through a rotating cylinder or drum type of washing apparatus or machine, showing the cylinder or drum in elevation and the article containers in nested relation thereon,

Figure 2 is a vertical transverse section through the washing apparatus or machine with the article containers removed from the cylinder or drum thereof,

Figure 3 is a section similar to that of Figure 2, but showing the article containers in nested position within the rotating cylinder or drum,

Figure 4 is an enlarged fragmentary plan view of adjacent hinged portions or sections of the securing means for retaining the article containers in position within a cylinder or drum, and the locking means for locking the portions or sections together,

Figure 5 is an enlarged side elevation of the fragmentary detail as shown in Figure 4,

Figure 6 is a vertical longitudinal section through a drying apparatus or tumbler, with the rotating cylinder or drum thereof in side elevation, and showing the article containers in nested position therein,

Figure 7 is a vertical transverse section of the same,

Figure 8 is a perspective view of one of the article containers per se,

Figure 9 is an enlarged fragmentary plan view of the upper or outer side of an article container, showing the article agitating member or rib and carrier handle thereof,

Figure 10 is a vertical section through the centrifugal moisture or water extracting machine, showing a set or group of the article containers nested therein.

Referring to the drawings, wherein like characters of reference designate corresponding parts throughout the several correlated views thereof, and more particularly to Figures 1 to 10 thereof, the cylinder or drum structures for both of the washing machine,

as shown in Figures 1 to 8 inclusive, and the drying machine or tumbler, as shown in Figures 6, 7 and 10 inclusive, are each constituted in circular end plates or walls 101 and intermediate partition plates or walls 102, which are coupled together in equidistantly spaced relation by radially disposed and longitudinally extending partition walls 103, the latter being preferably three in number between each pair of adjacent end plates and partition walls, and arranged in equidistantly spaced angular relation, or one hundred and twenty degrees (120°) apart. Projecting outwardly from the opposite end plates or walls 101 are supporting shafts 104, which are suitably journalled in bearings 105 carried by the opposite end walls 106 of each of the washing and tumbler machine casings 107 and 108. As shown in Figure 2, the circular intermediate partition plates or walls 102 of the cylinder or drum structure for the washing machine (Figures 1 to 3 inclusive) are preferably reticulated, as at 109, while those for the cylinder or drum structure for the drying machine or tumbler (Figures 6 and 7) are preferably solid. In both of the cylinder or drum structures, the radial partitions 103 are solid.

With the arrangement of the circular end and intermediate plates or partition walls 101 and 102, and the radial plates or walls 103, each cylinder or drum, so constructed, will provide for a plurality of compartments, preferably three in number in each space therebetween and in each of these several compartments an article receiving container or basket 110 is to be removably positioned or seated. As shown, these containers or baskets 110 will be of sector form corresponding to the shape of the several compartments of each cylinder or drum, and will have their several walls preferably made from heavy gauge open mesh wire secured to a shape retaining and reinforcing metal frame 111. One angular side wall 112 (Figure 8) of each of the containers or brackets 110 will preferably be formed separate from the remainder of the structure and hinged, as at 113, at the lower or inner longitudinal edge of the open side of the latter to function as a closure, and suitable fastenings 114 will be provided at its upper longitudinal edge to secure the same in closed position.

Extending longitudinally of the outer curved wall of each container or basket 110 and centrally therof, is an inwardly directed angular agitator member or rib 115, which is rigidly secured in place by being attached at its opposite ends to the metal frame 111, and is preferably, as shown, perforated substantially over its entire area. The opposite longitudinal sides of the member or rib 115 are preferably flanged, as at 116, to have adjacent portions of the outer wall fabric secured thereto by means of the fastenings or

rivets 117. A handle 118, preferably in the form of a suitable length of round metal rod, is secured at its opposite ends to the outer curved sides of the metal frame 111, and is supported thereby in spaced relation to and in the plane of the longitudinal center of the member or rib 115.

With a number of the containers or baskets 110, as thus constructed, the same are to be seated one within each of the several compartments of a cylinder or drum, and each circular set of the same between adjacent end and intermediate plates or partition walls 101 and 102 are to be securely held within their respective compartments by means of metal bands or straps encircled about the peripheral edges of the said plates or walls. Each of these bands or straps will preferably be formed to provide sections 119 arranged in end to end relation and in pairs with adjacent ends of the same hinged together, as at 119', and the hinge connections thereof secured to the outer edge of the longitudinal partition walls 103. The intermediate of the band sections 119 will be of a width to project equally for a distance to either side of the intermediate of the circular partition walls 102 and sufficiently to overlap the adjacent end portions of the containers or gaskets 110 nested in adjacent compartments, while the outer band sections will be of substantially less width and only sufficient to project inwardly from their encircling engagement about the end walls 101 to overlap the ends of the containers or baskets 110 adjacent thereto. The section 119 of each pair thereof are preferably of equal length and have their opposite unhinged ends, when disposed in their operative positions, spaced slightly apart in the plane of the longitudinal center of the adjacent compartments, so as to give clearance therebetween for their hinging movements to and from such operative positions. Arranged on the outer face of one of the latter ends of one of the sections 119 of each pair thereof is a lug or the like 120, which is to be engaged by a latching member or open loop 121 operatively connected to the outer side of the other of the adjacent end sections of the same. This member or loop 121 is hinged at its connected end, as at 122, to an intermediate portion of the outer side of an operating member or lever 123 which, in turn, is pivoted or hinged, as at 124, at one end to the outer side of the band section 119 to which it is complementary.

When the band sections 119, of each pair of the same, are moved to container or basket retaining position, the free end of the latching member or loop 121 will be engaged over lug 120, and the lever 123 swung on its hinge 124 in a direction away from the split or space between the adjacent ends of the sections 119 and downwardly against the outer

130

face of the section 119 on which it is carried, so that the free end of the member or loop 121 will be drawn under the angled portion of the lug 120, in which position of the parts the sections will be secured and locked in their operative positions.

The casing 107 will have an opening formed throughout its full length in its front and upper side, and of a sufficient area to permit of the quick and easy insertion of the containers or baskets 110 into the several compartments of the drum, and for their similar removal from position therein. This opening will be normally closed by a movable cover section 125, which is preferably arranged for rearward sliding movement to open position, substantially as shown in Figures 2 and 3; a handle, or handles, 126 being provided to facilitate its manipulation. It is to be noted that the lower edge of the opening will be disposed in a horizontal plane above the level of a maximum supply of washing fluid or rinsing water to be admitted to the casing.

Formed longitudinally of the bottom wall of the casing 107 and opening into the same is a channel or trough 127 which serves as a "settling" chamber for accumulations of dirt washed from clothes or the like placed within the containers or baskets 110, and to catch such articles as may be present in the clothes through carelessness of the owners.

Water is to be supplied to the casing 107 preferably from its rear side and in the horizontal plane of the axis of the drum through an inlet 128 connected to a suitable water supply not shown, while the soap or other cleansing material to be added thereto, may be introduced thereto through the opening in the front side of the casing as aforesaid.

With the several compartments of the drum occupied by a corresponding number of loaded containers or baskets 107, and the washing fluid formed within the casing 107, suitable power will be applied to one of the shaft sections 104 to impart the desired rotary or oscillatory motion to the drum. During the motion of the drum, and by reason of the segmental form of the containers or baskets 110, the articles to be washed therein will be subjected to a tumbling movement over the entire area of the opposite side walls and the outer peripheral wall thereof in each complete revolution of the drum, while the ribs 115 will act to jostle the articles in a manner

to keep the same in a comparatively loose or separated condition, except when the articles or fabrics move to the leading radial wall portions of each of the containers or baskets 110, in each revolution of the cylinder or drum, and in the downward direction of movement thereof, when the articles or fabrics will be subjected to a squeezing action between these walls and prior to being again immersed in the washing solution or suds in the lower part of the casing 107. As

the drum rotates, the washing fluid or rinsing water filling or nearly filling the lower half portion of the casing 107 will be successively scooped up by the solid longitudinal partition walls 103, as each of these walls move in an upward direction within the casing 107, and pocketed within the compartments. This retained washing fluid or rinsing water will be free to equally flood the several longitudinal sets of compartments, but will also be thrown outwardly through the articles or fabrics enclosed within the containers or baskets 110, during the upper half of each revolution of the drum, by the centrifugal force resulting from the rotation of the latter. A valve is provided in the water supply line leading to the inlet 128 to control the water admitted through the latter to the casing 107.

In adapting a washing machine of the type set forth for the desired subsequent and continuous rinsing operation, immediately following the completion of a washing operation, one or more outlets 129 will preferably be provided in one of the longitudinal side walls of the channel or trough 127, preferably in the forward of these walls, and stuffing boxes or the like 130 will be positioned on the outer ends of these outlets 129 to have angularly disposed discharge pipes or spouts 131 connected thereto for vertical swinging movements. The free ends of these pipes or spouts 131 will preferably be of angled formation to discharge the waste washing fluid or rinsing water to one side thereof. Thus, when the discharge pipes or spouts 131 are swung to their lowest position, which will place the discharge ends thereof below the level of the bottom wall of the channel or trough 127, the fluid contents of the casing 107 will be completely drained therefrom.

Now, when the discharge pipes or spouts 131 are swung in an upward direction to any desired position or to full vertical position, the washing fluid or rinse water will be retained within the casing 107, and the depth of the fluid or water to be admitted to the latter will be determined by the elevated position of the discharge ends of the pipes or spouts 131, with respect to the outlets 129. A suitable indicator device 132 may be associated with the movable pipes or spouts 131 to set the same at desired positions of operation.

The present invention contemplates the following method of operation of a washing machine as thus constructed and arranged, namely, that, with the casing devoid of any fluid content, the discharge pipes or spouts 131 will first be elevated to a position to give a desired depth to the fluid or water to be admitted to the casing, and then the control valve will be opened to allow water to enter the casing 107 at the inlet 128. When the depth of water has been reached within the

casing 107, the fact will be known by the discharge of water from the pipes or spouts 131, and the valve will then be closed. If 5 soap or other cleaning material has not previously been mixed with the water initially admitted to the casing 107, a sufficient amount of such material will now be introduced to the water, and power applied to the drum for a preliminary agitation of the water to assure 0 of the thorough mixing therewith of the cleansing agent. After the initial rotation of the drum, the same will be stopped and the articles or fabrics to be washed will then be placed within the cylinder, either in bulk, 5 when an ordinary cylinder or drum is employed, or in the individual wash containers 110 as hereinbefore explained. With the drum loaded, the cover 125 will be closed, and power again applied to the drum.

Now, after a predetermined period of operation of the machine has been permitted, the article or fabric contents of the drum will be ready for rinsing, and this is to be readily accomplished, without stopping the 5 rotation of the drum, by merely opening the water supply valve, when fresh water will enter the casing 107 at the inlet and displace the used washing fluid by causing the same to flow out of the discharge pipes or spouts 131. 0 This fresh water supply will be allowed to run through the casing 107 until the discharge from the outlet pipes or spouts 131 shows only clear water being present within the casing. The clear water will be permitted 5 to flow through the casing throughout a predetermined rinsing period, if desired, or when the discharge from the casing, at the outlet pipes or spouts 131, the valve may be intermittently opened and closed to allow intervals of non-flowing rinsing of the contents 0 of the drum. The discharge of the used washing fluid may be facilitated after a washing operation, if desired, by swinging the outlet pipes or spouts 131 to their lowest positions of movement, and, after the rinsing water shows clear in the discharge from the latter, the same may be again elevated.

After a washing and rinsing operation has been completed, the articles or fabrics, or the 5 individual containers of the same, will be removed from the casing 107, and will be transported to the moisture or water extracting machine as shown in Figure 10, which 10 comprises a casing 137, preferably of cylindrical form, which is supported in spaced relation above the floor level on members or legs 138. Mounted for horizontal movement within the casing 137 is a cylindrical receptacle 139, which is supported on the upper 15 end of a shaft 140 extending upwardly through the bottom wall of the casing. The lower end of the shaft 140 is journalled in a heavy bearing 141 incorporated in a strengthening member or spider 142 extending 20 between the supporting legs 138. A pul-

ley 143 is keyed on the shaft 140 above the bearing 141, and is operatively connected to a suitable source of power by means of a wrapping connector 144. A removable cover 145 is provided for the upper open end of the 25 casing 137.

In the proposed use of this extractor, a group of the loaded containers or baskets 110, just as they came from the washing machine, will be nested within the receptacle 139, and the cover 145 placed on the open end of the casing 137, when power will be applied at the pulley 143. The centrifugal force resulting from the rotation of the receptacle 139 will now act to throw the water content of the articles or fabrics within the containers or baskets 110 radially outward therefrom, and by having the side wall of the receptacle perforated, the extracted water will be discharged 30 into the casing 137. An outlet 146 is formed 35 in the bottom wall of the casing 137, and it preferably opens into a vertical bore 147 formed in one of the supporting legs 138, from the lower end of which the water is drained outwardly through a discharge pipe 148. To 40 prevent water within the casing 137 from accumulating about the shaft 140 and seeping downwardly of the same, an annular flange or ridge 137 is secured in concentrically spaced 45 relation about the shaft 140 on the bottom wall of the casing 137 for the purpose.

After the extracting operation has been completed, the several containers or baskets 110 are now transported to a drying apparatus or tumbler, shown by way of example in 50 Figures 11 and 12.

This drying machine or tumbler consists generally of a casing formed to provide a lower chamber 149, in which is housed a plurality of heating elements 150, an intermediate 55 cylindrical chamber 151 housing a drum structure as hereinbefore specifically described, and an upper air exhausting chamber 152. The upper side of the heating chamber 149 opens directly into the lower side of the 60 drum chamber 151, while the upper wall of the latter communicates with the upper exhaust chamber 152 through the medium of a longitudinal series of perforations 153. Heat from the chamber 149 and the heating 65 elements 150 therein will pass upward through the drum, within the intermediate chamber 151 and outwardly of the perforations 153 and into the exhaust chamber 152, while a suitable suction fan or the like 155 is 70 operable in the discharge outlet 156 of the exhaust chamber 152 to evacuate the heated air from the latter to atmosphere. Access 75 will be had to the interior of the drum chamber 151 through an opening in its front wall, 125 and this opening will be normally closed by a closure 157, which is hinged, as at 158, to the outer side of one of the horizontal edge 80 portions of the opening.

In making use of this form of drying 130

machine or tumbler, the groups of containers or baskets 110 will be nested in the compartments of the drum, through the front opening of the intermediate chamber 151, after the manner of the nesting of the same in the washing machine as heretofore explained, when the door 157 will be closed, and power applied to one of the shaft sections 104 to impart a rotary movement to the drum.

After the drying operation has been completed, the power will be disconnected from the drum, when the containers or baskets 110 will be released and removed from the drum and outwardly of the front opening of the intermediate chamber 151, for subsequent transporting to the packing department or room of the laundry, in the case of dry or damp washes, or to the starching and ironing department or room in the case of completely finished washes.

To facilitate the carrying out of the method contemplated by the invention, and to effect regularity and uniformity in the handling and transporting of the containers or baskets 110 from the receiving office or room of a laundry to the several machines as hereinbefore described, and from thence to the finishing department or room or the packaging and delivery department or room, a suitable form of vehicle or truck may be provided, such as is disclosed in Letters Patent No. 1,827,847, granted to me under date of October 20, 1931.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

Having thus fully described the invention, what is claimed is:

1. In combination, a rotatable drum for laundry machines and the like, formed to provide a plurality of groups of sector-shaped compartments in circular series about the same, sector-shaped containers for individual groups of fabrics to be laundered adapted to be removably seated within the said compartments, and means encircling said drum between each series of compartments and having movable sections common to companion containers in adjacent compartments for securing the containers in seated position therein.

2. In combination, a rotatable drum for laundry machines and the like, formed to provide a plurality of compartments about the same, containers for individual groups of fabrics to be laundered adapted to be nested within each of the said compartments, and means encircled about said drum between each of said compartments and having mov-

able sections common to companion containers in adjacent compartments for securing the containers in position therein.

3. In a laundry machine or the like, a rotatable drum formed to provide a plurality of compartments arranged in circular sets about the same, containers adapted to be removably seated within the said compartments, means encircling said drum between each circular group of the said compartments and having movable sections common to companion containers in adjacent compartments for securing the same in position therein, and means for securing each of the first named means in place.

4. The device as set forth in claim 3, wherein the last named means comprises separate devices on each of the said encircling means for latching the said movable sections in their positions of securement of the containers adjacent thereto.

5. The device as set forth in claim 3, wherein cooperative parts of a latching device are carried on adjacent ends of the said movable sections to secure the same in place during the rotation of said drum.

6. The device as set forth in claim 3, wherein the said movable sections are arranged in pairs hinged together at one of their ends and have parts of the said latching devices at their other ends adapted for cooperation with complementary parts thereof on the similar ends of adjacent movable sections.

In testimony whereof I affix my signature.

OTIS H. HULLINGS.
